(57) **CLAIM**

The ornamental design for paneling/trim board/decking element, as shown and described.

DESCRIPTION

FIG. 1 is a perspective view of the paneling/trim board/decking element of the present invention.

FIG. 2 is an elevation view showing the front of the paneling/trim board/decking element shown in FIG. 1, an elevation view showing the back being identical in appearance.

FIG. 3 is an elevation view showing the left side of the paneling/trim board/decking element shown in FIG. 1, an elevation view showing the right side being identical in appearance.

FIG. 4 is a top plan view of the paneling/trim board/decking element shown in FIG. 1, a bottom plan view being identical in appearance; and,

FIG. 5 is an enlargement of area 5 of FIG. 2 of the paneling/trim board/decking element.
